BRIQUETTING ROLL ASSEMBLY

Bethune G. Klugh, Birmingham, and George C. Perrine, Anniston, Ala., assignors to Monsanto Chemical Company, St. Louis, Mo., a corporation of Delaware

Application July 7, 1950, Serial No. 172,466

9 Claims. (Cl. 18—21)

1

The present invention relates to improvements in roll briquetting presses and more particularly to ejectors for removing briquettes which fail to discharge therefrom by gravity in the normal operating cycle.

The conventional type of briquetting roll press in most common use is one having hemispherical, semi-cylindrical or pyramidal depressions or pockets which are closely and regularly spaced over the peripheral faces of each of two coacting rolls so that the matched pockets at the compression surfaces continuously form briquettes as the rolls are rotated in synchronism. In briquetting rolls of this type, one half of each briquette lies below the peripheral plain surface thereof and consequently the ejectors of the instant invention are not applicable thereto.

In application Serial No. 100,628, filed June 22, 1949, in the name of the present applicants, a series of modified briquetting roll presses are described and/or illustrated. These presses yield briquettes which, after passing from their compression zone, have two full sides exposed, thus adapting them for removal by the ejector mechanisms hereinafter described.

In presses of the type referred to in the preceding paragraph, the material to be briquetted is shaped in cavities, pockets, depressions or enclosures on the surfaces of the rolls and when the resulting briquettes reach the proper position, they discharge by gravity from their respective pockets. However, it frequently happens that when the components of the mixture to be briquetted are not properly proportioned, some of the briquettes adhere to their pockets and re-pass to the feed zone with the undesirable result of eliminating the briquetting action of the rolls in those areas filled with adhering briquettes and also of subjecting the rolls to excessive strain and undue wear at these points.

It is, therefore, the primary object of the instant invention to provide novel briquette ejecting means for use with the modified briquetting rolls above described, whereby the above undesirable results are completely eliminated. Another object of the invention is to provide briquette ejectors in combination with the foregoing rolls whereby the power cost involved in the production of briquettes on said rolls is substantially reduced.

With the foregoing and other objects in view, the present invention resides in the combination and arrangement of parts and in the details of construction, hereinafter more fully de-

2

scribed and claimed, and illustrated in the accompanying drawings, in which

Figure 1 is a front elevational view of a briquetting roll assembly embodying the independent cam type of briquette ejector of the present invention.

Figure 2 is a vertical sectional view of the briquetting assembly of Figure 1 taken on line A—A.

Figure 3 is a partial horizontal sectional view 10 of the briquetting assembly of Figure 2 taken on line B—B.

Figure 4 is a front elevational view of a briquetting roll assembly embodying the toothed cammed ejector of the present invention.

15 Figure 5 is a partial vertical sectional view of the briquette roll of Figure 4 and also a front elevational view of the slide bar carrying the cam follower rolls and the briquette ejector pins.

Figure 6 is a side elevational view of the briquetting roll and the slide bar of Figure 5 taken as indicated by the arrows C—C.

Figure 7 is a horizontal sectional view taken 20 on line D—D of Figure 5.

Figure 8 is an end or axial view of a briquetting roll showing the end one of a bank of spring plunger briquette ejectors in its operating position.

25 Figure 9 is a front elevational view of a briquetting roll partially in section showing the ejector pins in the "out" position, that is, bearing on the teeth of the roll.

Figure 10 is a view similar to Figure 9, showing the ejector pins in "in" or operating position.

30 Figure 11 is a front elevational view of a briquetting roll with associated spring plunger briquette ejectors of modified design, the briquette roll being shown partially in section.

Figure 12 is a side elevational view taken on 40 line E—E of Figure 11.

Referring to Figures 1—3 inclusive, reference character 1 represents the spout for introducing the briquetting feed into the trough formed by the tangential contacting of the briquetting rolls

45 2 and 3.

Roll 2 has a series of circumferentially arranged V-shaped grooves 4, 5, 6 and 7 cut into its surface and also a series of longitudinal grooves 8 of similar shape and dimensions distributed around the entire periphery of the roll. The above grooves intersect each other at right angles and form quadrilateral pyramids in geometrically arranged pattern as shown in Figure 1.

50 The longitudinal grooves 8 retain the bri-

quettes since in the briquetting operation the pyramidal projections 4 on roll 3 occupy the space corresponding to the circumferential grooves 4, 5, 6 and 7 of roll 2.

Roll 2 is provided with a cylindrical cam groove 9 aligned with the longitudinal grooves 8. The cam follower 10 moving in the above groove, as the roll rotates, causes the slide bar 11 to reciprocate.

The cam follower 10 is mounted on shaft 12 and the latter in turn is rigidly connected in any suitable manner to slide bar 11. In order to prevent distortion of the above shaft, a reinforcing plate 13 is welded at its bottom and top edges to the slide bar 11 and shaft 12 respectively, and 15 on the opposite side of the slide bar 11 and shaft 12 a similar reinforcing plate (not shown) is provided.

The slide bar 11 is slidably mounted in guides 12' and 13' which are attached to the press frame members 14 and 15, respectively, which in turn provide support for the roll bearings 16 and 17. These bearings carry the drive shaft 18a of the briquetting roll 2.

The slide bar 11 carries a series of briquette ejector pins 18 (one for each peripheral row of briquette pockets) which are adjustably mounted so that their position with respect to the above briquetting roll may be varied as desired. This is accomplished by a series of set screws 19 which make it possible to rigidly secure the ejector pins 18 in their adjusted position.

Roll 3 is substantially identical in structure to briquetting roll 2 but differs therefrom in the following respect.

As indicated in Figure 3, roll 3 is equipped with an additional row of peripheral pyramidal projections, so as to provide lateral retaining walls for the briquettes formed in the outer peripheral rows of briquette pockets in roll 2. Moreover, since the outer rows of pyramidal projections in roll 2 are employed in providing lateral retaining walls for briquettes formed in the second and fifth peripheral rows of briquette pockets in roll 3, it is evident that the latter roll produces only four peripheral rows of briquettes. Except for the above difference, the cam groove, the briquetting surface and the method of mounting roll 3 are identical to the corresponding features of roll 2.

Roll 3 is provided with a briquette ejector mechanism including a slide bar 20, four briquette ejector pins 21 and a series of set screws 22 which permit adjustment of the position of the above pins with respect to the peripheral surface of the roll. The other elements of the ejector mechanism and the method of mounting and operating same are not shown since they are identical to the corresponding items illustrated and described in connection with the ejector mechanism for roll 2.

The briquette ejector mechanisms are shown located at a point directly below rolls 2 and 3, but the invention is not limited thereto as their position may be varied widely so long as they do not impede the free flow of the dislodged briquettes. However, it is preferred to locate each ejector mechanism in a position within the lower outer quadrants of each roll.

In the practice of the invention illustrated in Figures 1-3 inclusive, the charge to be briquetted is fed continuously to the briquetting rolls which are synchronously rotated so as to provide efficient enclosing and compression surfaces for shaping the briquette feed. This results in the

continuous formation of briquettes in both rolls and as they continue to rotate, the cam follower 10 moves in the cylindrical cam groove 9, thus causing the slide bar 11 to reciprocate. As soon as the briquetted material reaches the ejector mechanism, the slide bar 11 is moved to the right causing each ejector pin to dislodge a briquette from the adjacent peripheral row of briquettes. The further rotation of the rolls and the movement of the cam follower 10 in the cam groove 9 effects the shifting of the slide bar 11 to the left or to an inoperative position and allows the pyramidal projection to pass the ejector pin untouched. However, when the cam follower 10 moves again to the right in the cam groove, the slide bar 11 is moved to the right to dislodge another series of briquettes in the manner described above. These operations are repeated over and over as long as the rolls operate and material to be briquetted is fed thereto.

The operation of the ejector mechanism for briquetting roll 3 is identical to that described above in connection with roll 2 and it is, therefore, unnecessary to repeat same.

It is evident from the above description of Figures 1-3 that the outer peripheral rows of briquette pockets in roll 3 are not used in the continuous formation of briquettes on said roll and that it is not essential that the above rows be made discontinuous. Therefore, another embodiment of the invention involves the conversion of the above two peripheral rows of briquette pockets into continuous ridges of the same cross section encircling the roll.

The embodiment of the invention illustrated in Figures 1-3 is adapted for making briquettes on both rolls. However, it is also within the scope of the invention to form briquettes on only one roll. In such a modification, all of the peripheral rows of briquette pockets in roll 2 or 3 would be replaced by continuous ridges of the same cross section encircling the roll. Moreover, in the case of rolls with continuous peripheral ridges, the ejector mechanism would be omitted.

In the design described in the preceding paragraph, only one roll, namely, the longitudinally grooved one, need be driven and the other roll may float freely in the performance of its cooperating compression function.

As a further modification, instead of having the cam follower and cam groove on the same end of each roll as shown in Figures 1-3, they may be on one end of one roll and on the opposite end of the cooperating roll. Moreover, instead of being on the left end of each roll, the cam follower and cam groove may be both located on the right end of each roll.

Referring to Figures 4-7 inclusive, reference character 23 represents a briquetting roll similar to the one shown in Figure 1 except that it is provided with four instead of five peripheral rows of briquette pockets 24. This roll is supported by a shaft 25 which is journalled in bearings 26 and 27.

Reference character 28 represents a bar slidably mounted in guides 29 and 30 which are attached to press frame members 31 and 32, respectively, which in turn provide support for roll bearings 26 and 27, respectively.

The above slide bar 28 is provided with two vertically mounted fixed or adjustable briquette ejector pins 33 and 34 and two studs 35 and 36 which are rigidly or adjustably supported at an angle corresponding to beveled surfaces at the ends of the briquetting roll.

The studs 35 and 36 are constricted at their upper ends to provide bearings for cam follower rollers 37 and 38 respectively, which rollers are retained in position on the above bearings by means of nuts 39 and 40 respectively. These rollers 37 and 38 also serve as briquette ejectors.

The relative positions of the ejector pins 33 and 34 and the cam follower rollers 37 and 38 are clearly illustrated in Figures 6 and 7.

As in the case of the embodiment illustrated in Figures 1-3 inclusive, briquetting roll 23 cooperates with a similarly constructed roll (not shown) except that the latter is provided with one additional row of peripheral pyramidal projections so as to provide lateral retaining walls for the briquettes formed in the outer peripheral rows of briquette pockets in roll 23. Furthermore, since the outer rows of pyramidal projections on the cooperating roll are employed in providing lateral retaining walls for the briquettes formed in the outer peripheral rows of briquette pockets of roll 23, it is obvious that the former produces only three peripheral rows of briquettes as compared with four peripheral rows on roll 23.

The structure of the ejector mechanism for the cooperating roll and the means for mounting same are similar to the corresponding items described in connection with roll 23, the only difference being that the former ejector mechanism contains one instead of two ejector pins.

The briquette ejector mechanisms may be located in any of the positions mentioned in the description of Figures 1-3 inclusive, but it is preferred to locate each one in a position within the lower outer quadrant of each roll.

Referring particularly to Figures 4 and 5, it will be noted that cam follower roller 37 is in a position for ejecting a briquette in the first peripheral row of briquette pockets in roll 23 whereas cam follower roller 38 is rolling upon the conical surface of the briquetting roll 23 and therefore is not in a briquette ejecting position. Moreover, at this stage of the revolution of roll 23, the briquette ejector pin 34 is in a position for ejecting a briquette from the third peripheral row of briquette pockets while ejector pin 33 is to the right so as to pass between the second and third row of peripheral briquette pockets.

As the briquetting roll 23 rotates in the direction indicated by the arrow, the cam follower roller 37 moves upon the conical surface of the briquetting roll 23 and out of the position for ejecting a briquette from the first peripheral row of briquette pockets. This causes the slide bar 28 to be displaced to the left with the result that ejector pin 34 is shifted out of the position for ejecting a briquette from the third peripheral row of briquette pockets. While this is occurring, the cam follower roll 38 moves off of the conical surface of briquetting roll 23 into a position for ejecting a briquette from the last peripheral row of briquette pockets. As this takes place, the slide bar 28 is moved to the left, thus moving the ejector pin 33 into a position for ejecting a briquette from the second peripheral row of briquette pockets.

The continued rotation of briquette roll 23 causes the cam follower roller 37 to move off of the conical surface of roll 23 into a position for ejecting a briquette from the first peripheral row of briquette pockets. Simultaneously therewith, the slide bar 28 is shifted to the right, thus displacing ejector pin 34 to a position for ejecting briquettes from the third peripheral row of briquette pockets.

The above operations are repeated over and over with the result that all of the briquettes are continuously ejected from the four peripheral rows of briquette pockets in roll 23. This eliminates any blind spots in the roll due to the filling up of the briquette pockets with adhering briquettes and also the resulting undue wear and strain on the roll at these points.

The operation of the ejector mechanism for the cooperating roll is identical with that described in connection with roll 23 and hence further description is unnecessary.

Moreover, the ejector mechanisms of Figures 4-7 inclusive may be used with the various briquetting roll combinations described in connection with Figures 1-3 inclusive.

Figures 8-10 inclusive illustrate another type of briquette ejecting device. This device comprises a plurality of slidably mounted plungers 41 retained in cylinder guides 42 which are carried by frame bar 43, the latter being rigidly attached at its ends in any suitable manner to the frame of the machine or press (not shown).

The upper ends of the cylinder guides 42 are provided with bushings 44 which serve as guides for the constricted sections 45 of plungers 41. These constricted sections are threaded at their ends to accommodate nuts 46 and 47 which are used to adjust the maximum outward travel of plungers 41 when ejecting a briquette.

The springs 48 continuously apply force against shoulders 49 and thus normally press plungers 41 outwardly against briquetting roll 50.

The above-described briquette ejecting device is placed in the same positions with respect to briquetting roll 50 as illustrated and described in connection with Figures 1-7 inclusive.

The briquetting roll 50 and the cooperating briquetting roll (not shown) are similar in structure to rolls 2 and 3 respectively of Figure 2.

It will be noted that the peripheral rows of briquette pockets 51 are interrupted by pyramidal projections 52 and that when the plungers 41 are not in a briquette ejecting position, they are forced by the action of springs 48 against the above projections in the manner illustrated in Figure 9. However, as soon as the roll 50 rotates further, the plungers move into a position where they are projected into the briquette pockets 51, thus dislodging the briquettes 53 therefrom. As the rotation of roll 50 continues, the plungers 41 are moved to an inoperative position by camming action of the pyramidal projections 52, the tapered portion 54 of the above plungers serving to facilitate the above operation. Thus, with the rotation of the roll 50, the plungers 41 are continuously forced into and out of briquette pockets 51 by the action of the coiled springs 48 and the camming action of the pyramidal projections 52 with the result that the briquettes are continuously removed from the above pockets as rapidly as they are formed therein.

The construction and operation of the ejector mechanism for the cooperating briquetting roll is the same as the corresponding items described in connection with roll 50, the only difference being in the number of plungers used in the ejector mechanism. Thus, for the reasons hereinbefore indicated in connection with Figures 1-7, the cooperating roll will have one less row of active peripheral briquette pockets and, therefore, it requires one less ejector pin or plunger.

75. The ejector mechanism of Figures 8-10 inclu-

sive may also be employed with the various briquetting roll combinations described in connection with Figures 1-3 inclusive.

Referring to the modified spring plunger type of briquette ejector illustrated in Figures 11 and 12, reference character 55 represents the housing for briquette ejector pins 56, 57, 58 and 59, the beveled ends of which extend through openings 60 into contact with briquetting roll 61. To the body of each of the ejector pins, there are welded or otherwise secured collars 62 which support, restrain or retain ball bearing assemblies 63. Coiled springs 64 encircling the ejector pins are located beneath the ball bearing assemblies 63, the above springs being supported at the bottom by recesses 65 in the top of tension adjusting plugs 66. The threaded adjusting plugs 66 are screwed into the bottom sections 67 and 68 of the housing 55.

The springs 64 apply pressure against the outer race 69 of the ball bearing assemblies 63, which pressure is transmitted to the under surface of collar 62, thus causing the ejector pins 56, 57, 58 and 59 to be normally forced out against the surface of the briquetting roll 61. The tension on the springs 64 is adjusted by screwing the adjusting plugs 66 inwardly or outwardly.

A series of lugs 70 corresponding in number to the ejector pins are rigidly secured to the bottom surface of the top of the housing 55. These lugs are recessed so as to accommodate coiled springs 71 which bear against the outer race 69 of ball bearing assemblies 63. The springs 71 press against the ball bearing assemblies 63 and thus exert lateral pressure against the ejector pins.

The lower ends of the ejector pins 56, 57, 58 and 59 have a diameter somewhat less than the bore of the adjusting plugs 66. This arrangement is designed to permit the lateral movement of the above pins so that once they move to a briquette ejecting position, the coiled springs 71 can force them against the briquettes and thus dislodge same from the roll 61.

The housing 55 is supported by frame bar 72 which is secured at its ends in any suitable manner to the fixed frame (not shown) in which the briquetting roll 61 is mounted.

As shown in Figures 11 and 12, the ejector pins 56 and 58 are in a position for ejecting briquettes from the fifth and third peripheral rows of briquette pockets, whereas pins 57 and 59 are each pressed laterally against a pyramidal projection in the fourth and second peripheral rows of briquette pockets in roll 61. As the roll 61 rotates, the pins 56 and 58 are moved by the camming action of the adjacent pyramidal projections to a position where they exert lateral pressure against a pyramidal projection in the fifth and third row of briquette pockets. While this is taking place, the pins 57 and 59 move to a position where they are projected laterally against a briquette in the fourth and second peripheral rows of briquette pockets.

As the roll 61 continues in its cycle of rotation, the pins 56 and 58 again move into a position for ejecting briquettes from the fifth and third peripheral rows of briquette pockets and simultaneously therewith the pins 57 and 59 move behind pyramidal projections and thus are placed in a position where they cannot eject briquettes.

The above operations are repeated with the continued rotation of the roll 61 and thus the briquettes are dislodged therefrom as rapidly as they are formed.

The construction of the smaller cooperating briquette roll (not shown) is similar to that of roll 61 except that it contains one less peripheral row of pyramidal projections. The reason for this is the same as that advanced in the description of the other embodiments of the invention.

The structure and operation of the ejector mechanism for the smaller cooperating roll and the means for mounting same are similar to the corresponding items described in connection with roll 61, the only difference being that the ejector for the cooperating roll has five instead of four ejector pins.

The position of the ejecting mechanisms with respect to roll 61 and the cooperating roll may be varied widely, but as in the case of the previously described embodiments of the instant invention, it is preferred to locate the ejector mechanisms in a position within the lower outer quadrant of each roll.

The ejector mechanism of Figures 11 and 12 may also be used with the various briquetting roll combinations described in detail in connection with Figures 1-3.

The above description has been confined to the use of the illustrated ejector mechanisms in combination with briquetting rolls adapted to form tetrahedral briquettes on one or both rolls. However, the invention is not restricted thereto as the above ejector mechanisms are applicable to all the briquetting roll assemblies described and/or illustrated in the above application, which produce briquettes in situ with exposed surfaces for the full depth of the briquettes or substantially so.

Moreover, the above description has been limited to mechanically operated briquette ejectors, but it is to be understood that the invention is much broader in scope. For example, the briquette ejector pins or plungers may be operated by pneumatic, hydraulic or electrical means.

It is evident from the foregoing description that the briquette ejectors of the instant invention provide a solution to the problem which accompanies the adherence of the briquettes to their respective pockets. However, this is not the only function performed by the above ejectors; they effect a substantial reduction in the power consumption involved in the production of briquettes on the rolls with which they are employed.

For example, within the range of moisture required for satisfactory briquetting, the power consumption varies inversely with the moisture content of the material to be briquetted. With a hygroscopic water content of 10% by weight, a mixture of finely divided plastic clay bearing phosphate ore and bituminous coal can be formed into sufficiently strong stable briquettes for subsequent treatment, but at such moisture content the briquettes tend to adhere to the inner surface of the briquette pocket and therefore fail to discharge therefrom by gravity. In such case, in order to produce briquettes which are not subject to the above disadvantage, it is necessary to reduce the hygroscopic water content to about 8% by weight or slightly thereunder. However, with this reduced water content, the power consumption has been found in practice to be over twice that with the higher water content described. Thus, with the ejector removing the naturally adhering briquettes having the higher water content, it is obvious that a great reduction in power consumption is thereby effected.

The application hereinbefore referred to is in-

corporated by reference in the present specification for the purpose of further illustrating the types of briquetting roll assemblies to which the instant invention is applicable.

It is to be understood that changes in the size, form and construction of the various parts of our improved briquetting machine can be made and substituted for those herein shown and described, without departing from the spirit of the invention, the scope of which is set forth in the appended claims.

We claim:

1. A briquetting roll assembly comprising in combination a pair of opposed contacting rolls which rotate in the same direction at the point of contact, each roll having uniformly spaced parallel V-shaped peripheral grooves and adjacent parallel peripheral ridges, at least one of said rolls having axial angular grooves intersecting said V-shaped peripheral grooves and peripheral angular ridges at right angles on said one roll and said peripheral ridges on the other roll closely intermeshing with the peripheral grooves on said one roll at the point of contact of said rolls and providing lateral closures for the axial grooves on said one roll and thereby forming a series of completely separated mold cavities on said one roll; and an ejector means for laterally dislodging the adhering briquettes formed in said one roll, said ejector means being mounted adjacent to said one roll and being actuated at least in part by the rotary movement thereof.

2. A briquetting roll assembly comprising in combination a pair of opposed contacting rolls of substantially the same diameter which rotate in the same direction at the same or substantially the same peripheral speed at the point of contact, each roll having uniformly spaced parallel V-shaped peripheral grooves and adjacent parallel peripheral ridges, at least one of said rolls having axial angular grooves intersecting said V-shaped peripheral grooves and peripheral angular ridges at right angles on said one roll and said peripheral ridges on the other roll closely intermeshing with the peripheral grooves on said one roll at the point of contact of said rolls and providing lateral closures for the axial grooves on said one roll and thereby forming a series of completely separated mold cavities on said one roll; and an ejector means for laterally dislodging the adhering briquettes formed in said one roll, said ejector means being mounted adjacent to said one roll and being actuated at least in part by the rotary movement thereof.

3. A briquetting roll assembly comprising in combination a pair of opposed contacting rolls of substantially the same diameter which rotate in the same direction at the same or substantially the same peripheral speed at the point of contact, each roll having uniformly spaced parallel V-shaped peripheral grooves and adjacent parallel peripheral ridges, one of said rolls having axial angular grooves intersecting said V-shaped peripheral grooves and peripheral angular ridges at right angles on said one roll and said peripheral ridges on the other roll closely intermeshing with the peripheral grooves on said one roll at the point of contact of said rolls and providing lateral closures for the axial grooves on said one roll and thereby forming a series of completely separated mold cavities on said one roll; and an ejector means for laterally dislodging the adhering briquettes formed in said one roll, said ejector means being mounted adjacent to said

10
one roll and being actuated at least in part by the rotary movement thereof.

4. A briquetting roll assembly comprising in combination a pair of similar opposed contacting rolls which rotate in the same direction and at the same peripheral speed at the point of contact, each roll having uniformly spaced parallel V-shaped peripheral grooves, adjacent parallel peripheral ridges and parallel axial angular grooves intersecting said V-shaped peripheral grooves and peripheral angular ridges at right angles on each roll and said peripheral ridges on each roll closely intermeshing with the peripheral grooves on the other roll at the point of contact of said rolls and providing lateral closures for the axial grooves on said other roll and thereby forming a series of completely separated mold cavities on said other roll; and a briquette ejecting means for at least one of said rolls comprising a cylindrical cam groove aligned with the axial grooves on said one roll, a slide bar adjacent to said one roll carrying a series of briquette ejector pins and a cam follower roller which moves in said cylindrical cam groove, said cylindrical cam groove and said cam follower coacting with each other and the rotary movement of said one roll to alternately move said ejector pins into and out of the axial grooves in said one roll to dislodge the adhering briquettes formed therein.

5. A briquetting roll assembly comprising in combination a pair of similar opposed contacting rolls which rotate in the same direction and at the same peripheral speed at the point of contact, each roll having uniformly spaced parallel V-shaped peripheral grooves, adjacent parallel peripheral ridges and parallel axial angular grooves intersecting said V-shaped peripheral grooves and peripheral angular ridges at right angles on each roll and said peripheral ridges on each roll closely intermeshing with the peripheral grooves on the other roll at the point of contact of said rolls and providing lateral closures for the axial grooves on said other roll and thereby forming a series of completely separated mold cavities on said other roll; and a briquette ejecting means for at least one of said rolls comprising a slide bar carrying non-aligned cam follower rollers which alternately engage the conical surfaces and move into the axial grooves at the ends of said one roll and intermediate briquette ejector pins aligned with each of said rollers which move into and out of said axial grooves in said one roll, said cam follower rollers coacting with said conical surfaces, said axial grooves and the rotary movement of said one roll to move said rollers and said aligned ejector pins into and out of said axial grooves in said one roll to dislodge the adhering briquettes formed therein.

6. A briquetting roll assembly comprising in combination a pair of similar opposed contacting rolls which rotate in the same direction and at the same peripheral speed at the point of contact, each roll having uniformly spaced parallel V-shaped peripheral grooves, adjacent parallel peripheral ridges and parallel axial angular grooves intersecting said V-shaped peripheral grooves and peripheral angular ridges at right angles on each roll and said peripheral ridges on each roll closely intermeshing with the peripheral grooves on the other roll at the point of contact of said rolls and providing lateral closures for the axial grooves on said other roll and thereby forming a series of completely separated mold cavities on said other roll; and a briquette ejecting means for at least one of said rolls comprising a series of aligned

spring-actuated reciprocating plungers which in their inoperative position are pressed against the peripheral ridges of said one roll and in their operative position are pressed into the axial grooves of said one roll, said plungers being alternately forced inwardly into said axial grooves on said one roll by the action of said spring and outwardly therefrom by the camming action of the peripheral ridges on said one roll.

7. A briquetting roll assembly comprising in combination a pair of similar opposed contacting rolls which rotate in the same direction and at the same peripheral speed at the point of contact, each roll having uniformly spaced parallel V-shaped peripheral grooves, adjacent parallel peripheral ridges and parallel axial angular grooves intersecting said V-shaped peripheral grooves and peripheral angular ridges at right angles on each roll and said peripheral ridges on each roll closely intermeshing with the peripheral grooves on the other roll at the point of contact of said rolls and providing lateral closures for the axial grooves on said other roll and thereby forming a series of completely separated mold cavities on said other roll; and an ejecting means for at least one of said rolls comprising a fixed frame bar carrying a plurality of substantially parallel rows of spring-actuated ejector pins which in their inoperative position are pressed against the angular peripheral ridges of said one roll and in their operative position are thrust into the axial grooves of said one roll, said ejector pins being alternately forced inwardly into the axial grooves of said one roll by the action of a spring and outwardly therefrom by the camming action of the angular peripheral ridges on said one roll.

8. A briquetting roll assembly comprising in combination a pair of similar opposed contacting rolls which rotate in the same direction and at the same peripheral speed at the point of contact, each roll having uniformly spaced parallel V-shaped peripheral grooves, adjacent parallel angular peripheral ridges and parallel axial V-shaped grooves intersecting said V-shaped peripheral grooves and peripheral angular ridges at right angles on each roll and said peripheral ridges on each roll closely intermeshing with the peripheral grooves on the other roll at the point of contact of said rolls and providing lateral closures for the axial grooves on said other roll and thereby forming a series of completely sep-

5 arated mold cavities on said other roll, said angular surfaces of said peripheral ridges on each roll terminating in a line lying in a plane defined by the outer periphery of each roll; and an ejector means for at least one roll for laterally dislodging the adhering briquettes formed therein, said ejector means being mounted adjacent to said one roll and being actuated at least in part by the rotary movement thereof.

15 9. A briquetting roll assembly comprising in combination a pair of similar opposed contacting rolls which rotate in the same direction and at the same peripheral speed at the point of contact, each roll having uniformly spaced parallel V-shaped peripheral grooves, adjacent parallel angular peripheral ridges and parallel axial angular grooves of trapezoidal cross section intersecting said V-shaped peripheral grooves and peripheral angular ridges at right angles on each roll and said peripheral ridges on each roll closely intermeshing with the peripheral grooves on the other roll at the point of contact of said rolls and providing lateral closures for the axial grooves on said other roll and thereby forming a series of completely separated mold cavities on said other roll; and an ejector means for at least one roll for laterally dislodging the adhering briquettes formed therein, said ejector means being mounted adjacent to said one roll and being actuated at least in part by the rotary movement thereof.

BETHUNE G. KLUGH.
